ABSTRACT OF THE DISCLOSURE

Mounting of points on which fabric is impaled in a knitwear linking machine by providing die cast segmental blocks fitting end to end in ring-like manner in a channelled ring carriage, a group of the points being cast in each block, and the blocks being secured to the base of the channelled ring carriage by screws sunk in the blocks, any of the blocks being thereby removable for repair or replacement purposes without removal of any other parts.

Background of the invention

This invention is for improvements in or relating to linking machines of the type adapted for uniting knitted fabrics and provided with points upon which superimposed loops of the fabrics are impaled and the invention concerns the mounting of the points.

In circular linking machines the usual dial assembly for carrying the points comprises a ring carriage having underneath gear teeth (generally 280) and an upper annular recess, a tricked dial ring fitted on the outer wall formed by the recess, points of crank form fitting so that parts thereof are received in the tricks of the dial ring, the walls of the tricks being riveted or peined over these parts of the points, and other parts of the points lying in the base of the annular recess, and cap segments which are secured in the annular recess, by screws, over said other parts of the points.

In the event of breakage of a point, without other damage, the securing cap segment and the point could be removed and a new point fitted, but if the walls of the trick in the dial ring are also damaged, it then becomes necessary to remove all the cap segments, remove the tricked dial ring and to fit a new dial ring followed by re-fitting the cap segments. In addition to the time and labour involved and the loss of production time, the tricked dial rings are comparatively expensive precision components being made of brass and requiring several machine tool operations and cutting of a multiplicity of tricks for locating the points. Furthermore when fitting the points in the tricks, further time and labour is involved in pliering the points. A still further undesirable feature of the usual arrangement is that the cap segments are for certain commercial reasons made of a frangible material which leads to breakages while fitting the segments to the ring carriage.

An object of the invention is to provide means for mounting the points which are of such improved construction that in the event of a point breaking, the fault can be rectified by performing a comparatively simple removal and fitting operation with a minimum of expense, time and labour and without breakage of cap segments.

The invention provides a linking machine in which the points are provided in end to end groups, the points of each group being set in a metal block, and the blocks being secured end to end in a channelled support by screws. In a circular type linking machine the channelled support is the usual ring carriage, and the mounting blocks of the points are of segmental form. Conveniently the number of blocks is equal to the number of teeth in the usual gear ring under the ring carriage divided by the

2

number of teeth in the usual pinion meshing with the gear ring. Conveniently also the number of points in each mounting block is equal to the number of teeth in the usual changeable worm gear mounted co-axially with said pinion. Each block may have a base portion which rests on the base of the channel in the channelled support, and front and rear portions which overlie front and rear portions of the support with clearance between the opposed surfaces. The machine may have a needle or a yarn feeder overlying the path of the blocks, and the blocks are secured to the support by Allen screws to allow clearway for the blocks passed the needle or yarn feeder.

The invention also provides a circular linking machine having a channelled ring carriage mounted for rotation and formed underneath with a ring gear, drive transmitting means including a pinion meshing with the ring gear and a co-axial worm gear which is interchangeable with similar gears having different numbers of teeth and is driven by an electric motor, segmental blocks secured end to end in the channel of the ring carriage, the number of blocks being equal to the number of teeth on the ring gear divided by the number of teeth on the pinion, and each block having a group of points set in it, the number of points in each group being equal to the number of teeth in the said worm gear. Conveniently the machine comprises a rotatably mounted channelled ring carriage, a needle having a path of movement over the ring carriage, a yarn feeder for feeding yarn to the needle, drive transmitting means adapted to impart drive to said ring carriage, needle, and yarn feeder and including a common drive shaft driven by an electric motor, and blocks of points removably secured in end to end relationship in the ring carriage.

The invention further provides in or for the machine; a metal block mounting a group of points and being a die-casting.

The above and other features of the invention set out in the appended claims are incorporated in the construction which will now be described, as a specific embodiment with reference to the accompanying drawings in which:

FIGURE 1 is a side view of a linking machine according to the invention.

FIGURE 2 is a plan view of part of the linking machine.

FIGURE 3 is an enlarged cross sectional view of a ring carriage and attached blocks of points.

FIGURE 4 is a perspective view of part of the ring carriage and a block of points secured therein.

Referring to FIGURES 1 and 2 a linking machine is represented by support casing 1 which overhangs from a supporting pillar 2 and which supports a ring carriage 3 in rotatably mounted manner.

The casing 1 houses motion transmitting mechanism indicated generally at 4 for a needle 5 which has a path of movement across the ring carriage. This motion transmitting mechanism includes a connecting rod 6 extending from an eccentric 7 on a shaft 8 driven by an electric motor 9 through belt and pulley means 10.

At the inner side of the ring carriage is motion transmitting mechanism indicated generally at 11 for a yarn feeder 12 which overlies the ring carriage, and this motion transmitting mechanism includes a connecting rod 13 extending from an eccentric 14 on said shaft 8.

For driving the ring carriage it has on its underside a ring gear 16 with which meshes a pinion 15 on a spindle 17, and co-axial with the pinion 15 and on the spindle 17 there is a worm gear 18 which is interchangeable with similar gears having different numbers of teeth. This worm gear 18 meshes with a worm 19 on a spindle 20 on which there is also a worm gear 21 meshing with a worm 22 on

said shaft 8. The spindle 20 is supported from the shaft 8 to be displaceable about the shafts axis to allow for the different sizes of worm gears such as 18. A spring (not shown) biases the spindle towards engagement of the worm gear 18 and worm 19.

The ring carriage 3 is of usual channelled form shown particularly in FIGURES 3 and 4 the channel recess 3a forming a base wall 3b, a front wall 3c, and a rear wall 3d which includes an inner side shoulder 3e and an outer side rebate 3f.

For mounting the usual ring of points P on the ring carriage, the usual tricked dial ring of brass and the usual cap segments for securing the usually cranked points to the carriage, are dispensed with.

Instead, groups of shortened comparatively straight points are set each in a metal block 23, and the blocks are secured in readily removable manner in the ring carriage.

More specifically each block is a die casting of segmental form with radial end faces 23a, 23b, FIGURE 4, and they are mounted end to end as shown in FIGURE 2.

Each block 23 is die cast with the group of points P cast in it, and each block comprises a base portion 23c, FIGURE 3, a rear portion 23d formed with a rabbet 23e which is deeper than the shoulder 3e of the ring carriage 3, and a front portion 23f which projects upwardly and provides a forwardly projecting portion 23g to which the points P are cast.

Each block is secured in the ring carriage, with the base 23c of the block resting on the base wall 3b of the ring carriage, and with a clearance between the rear rabbet 23e and shoulder 3e and between the front portion 23f and the wall 3c, by two Allen screws 24. These screws 24 are of button headed type for which purpose each block has recesses 25 to receive the button head 24a.

The ring gear usually has 280 teeth and the pinion 16 usually has 20 teeth, and for satisfactory operation of the segmented block arrangement of points, the number of blocks is equal to the number (280) of teeth on the ring gear divided by the number (20) of teeth on the pinion, the number of blocks being therefore 14, and therefore each revolution of the pinion is accompanied by the passage of a block passed a given spot.

Since points of different pitches are employed in linking machines, there is provided a range of the worm gears 18 having different numbers of teeth, and there is also provided a range of blocks of points in which the points are of different pitch spacings. In each instance, since the advance of one tooth of the worm gear should be accompanied by the passage of one point passed a given spot, the number of points in each block is equal to the number of teeth on the associated worm gear.

In the event of breakage of one or more points, it is necessary only to remove a mounting block simply by taking out the two screws and replacing it by another block of the points.

It will be appreciated that this arrangement is considerably less troublesome, less time consuming, and less costly than in the usual arrangement when the usual costly tricked ring of brass has to be removed and replaced, after removing all the cap segments and followed by re-fitting of all the cap segments. No pliering of points is necessary and there are no breakages of cap segments.

What is claimed is:

1. A linking machine having in combination a channelled ring carriage with a front wall, a series of die cast

segmental blocks fitting in said channel ring carriage in mutual end to end relation forming a ring-like assembly of said blocks, each said block having an upper forwardly projecting portion projecting over said front wall of said channelled ring carriage and a series of radial substantially straight points cast in said upper forwardly projecting portion of said channelled ring carriage with a predetermined pitch spacing and projecting beyond said front wall of said channelled ring carriage, and screws removably securing said blocks to said channelled ring carriage, whereby any of said blocks can be removed with their own series of points cast in them and be replaced by other similar blocks having their own series of points similarly cast in them with the same or different pitch spacing.

2. A linking machine having in combination a channelled ring carriage with a front wall and a base wall, a series of die cast segmental blocks fitting on said base wall in said channelled ring carriage in mutual end to end relation forming a ring-like assembly of said blocks, each said block having an upper forwardly projecting portion projecting over said front wall of said channelled ring carriage and a series of radial substantially straight points cast in said upper forwardly projecting portion of said channelled ring carriage with a predetermined pitch spacing and projecting beyond said front wall of said channelled ring carriage, and screws sunk in said blocks and removably securing said blocks to said base wall of said channelled ring carriage, whereby any of said blocks can be removed with their own series of points cast in them and be replaced by other similar blocks having their own series of points similarly cast in them with the same or different pitch spacing.

3. A linking machine having in combination a channelled ring carriage with a front wall and a base wall and an underneath gear wheel, a driven pinion meshing with said gear wheel, a driving worm gear co-axial with said pinion, a number of die cast segmental blocks equal to the quotient of the number of teeth in said gear ring and the number of teeth in said pinion and in mutual end to end relation forming a ring-like assembly of said blocks, each said block having an upper forwardly projecting portion projecting over said front wall of said channelled ring carriage and a number of radial substantially straight points equal to the number of teeth in said worm gear cast in said upper forwardly projecting portion of said channelled ring carriage with a predetermined pitch spacing, and projecting beyond said front wall of said channelled ring carriage, and screws removably securing said blocks to said channelled ring carriage, whereby said worm gear and any of said blocks can be removed with the blocks' own points cast in them and be replaced by another worm gear and other similar blocks having their own series of points similarly cast in them with the same or different pitch spacing.
